UNITED STATES PATENT OFFICE

GOYN D. MacKRELL, OF BROOKLYN, NEW YORK, ASSIGNOR TO GURNEY SECURITY PAPER COMPANY, INC., OF BROOKLYN, NEW YORK, A CORPORATION OF NEW YORK

DESIGN FOR PAPER

Application filed November 4, 1929. Serial No. 33,320. Term of patent 14 years.

To all whom it may concern:

Be it known that I, GOYN D. MacKRELL, a citizen of the United States, residing at Brooklyn, in the county of Kings and State of New York, have invented a new, original, and ornamental Design for Paper, of which the following is a specification, reference being had to the accompanying drawing, forming part thereof.

The figure is a plan view of a sheet of paper, showing my new design.

The design consists of vertically spaced horizontal straight lines, the lines being broken into sections with the respective ends of each section being disposed angularly in opposite directions. Furthermore, the adjacent ends of the sections are arranged intermediate the ends of the superjacent and subjacent sections.

I claim:

The ornamental design for paper, as shown and described.

GOYN D. MacKRELL.
